UNITED STATES PATENT OFFICE.

GEORGE M. WILLIS, OF CHICAGO, ILLINOIS, ASSIGNOR TO CHECKOMETER SALES CO.,
A CORPORATION.

CHECK WRITER.

Application filed March 3, 1924. Serial No. 696,421.

To all whom it may concern:

Be it known that I, GEORGE M. WILLIS, a citizen of the United States, residing at Chicago, in the county of Cook and State of Illinois, have invented a certain new and useful Improvement in Check Writers, of which the following is a full, clear, concise, and exact description, reference being had to the accompanying drawings, forming a part of this specification.

This invention relates to improvements in check-writers and the like, and its objects are to make the impression produced on the check or other instrument more distinct and of better appearance and more difficult to alter or remove, and to provide an improved printing mechanism for producing such an impression, and a printing mechanism the construction, operation, and co-action between the elements of which is a general improvement over the printing mechanisms heretofore provided.

The invention is illustrated in the accompanying drawings in which,

Fig. 1 is a longitudinal section through a device embodying the invention and adapted for producing an impression in accordance therewith;

Fig. 2 is a transverse section on line 2—2 of Fig. 1;

Fig. 3 is a fragmentary bottom plan view of one of the type bars;

Fig. 4 is a fragmentary top plan view of one form of platen;

Fig. 5 is a fragmentary top view of another form of platen;

Fig. 6 is a detail section on line 6—6 of Fig. 3;

Fig. 7 is a section on line 7—7 of Fig. 4;

Fig. 8 is a section on line 8—8 of Fig. 5;

Fig. 9 shows fragmentarily a check printed or impressed with the platen shown in Fig. 4; and

Fig. 10 is a similar view of a check printed or impressed with the platen shown in Fig. 5.

The improvements of the present invention are attained in conjunction with devices of the class shown and described in my prior Patent No. 1,321,348 granted November 11, 1919, and in my copending applications, Serial No. 481,632 filed June 30, 1921, and Serial No. 563,229 filed May 24, 1922. Generally speaking, devices of this class include a plurality of longitudinally shiftable print-

ing bars, each of which is provided with a set of consecutively arranged numeral type or characters co-operable with a suitable platen, the type bars being independently adjustable so that the desired characters may be aligned to co-operate with the platen and impress or print on the instrument the amount for which the instrument is drawn.

The device shown comprises a frame 5 having an opening 6 through which the check or other instrument to be protected is inserted, the printing line *a—a* being defined by the dot and dash lines of Fig. 1. The bottom of opening 6 is defined by a plate 8 and along the top of said opening are a pair of upper plates 9 and 10. Plates 9 and 10 are spaced apart along line *a—a* and plate 8 has a transverse opening 11 to permit inking the printing characters and perforating and printing or impressing upon the check through said space and opening. The type bars are mounted for longitudinal sliding or shifting movement upon plates 9 and 10, the bars carrying the tens and unit of tens or cents characters and designated 7' being mounted side by side between a longitudinal block 12 of 1 formation and a block 13 and the bars 7 carrying the dollars, tens-of-dollars, hundreds-of-dollars, etc., characters are mounted side by side between bar 12 and a bar 14. Block 12 carries in line *a—a* the characters "cts". Block 12 carries in line *a—a* the word "and" and bar 14 is enlarged along said line and is adapted to carry a trade symbol or other character or characters in line with the printing characters in printing position so that in making the impression the desired amount will be impressed and said amount will be preceded by a symbol or character which may bear a definite relation to the signature itself.

The device is enclosed in a sheet metal housing 15 having a bottom 16 and a top or cover 17. Each type bar 7 and 7' has an operating finger 19. Fingers 19 extend through parallel slots 20 in the cover 17. A detent finger 21 on each type bar 7 and 7' cooperates with the transverse corrugations of a corrugated aligning plate or sheet 22, to center or align the selected characters transversely in line *a—a*. Each bar 7 and 7' has an indicating strip 23 bearing numerals or characters corresponding to the characters on the type bar and superposed

thereabove to be exposed through windows 24 and indicate the setting of the printing characters of the machine.

The inking pad 25 for inking the printing characters is carried by the plate 26 hinged with an arm or plate 27 upon a shaft 28 carried at its opposite ends by a pair of arms 29 pivoted at their lower ends at 30 upon opposite sides of frame 5. Arm or plate 27 carries the perforator, which comprises two groups 31 and 32 of relatively thin needles, one group 31 for perforating the area of the check in which the amount payable is impressed and the other for perforating the area in which the payee's name is written or impressed as shown at 90 and 92 respectively in Figures 9 and 10. The platen 33 is carried by a plate 34 hingedly or swingably mounted upon a shaft 35 carried at its opposite ends by arms 36 pivoted at their lower ends at 37 upon opposite sides of frame 5. Arms 29 and 36 are connected by links 38. An operating or crank shaft 40 has an operating handle or arm 41 and a cam or operating block 42 fixed on the shaft cooperates with a lug projecting from an arm 43 pivoted on a shaft 44 carried by arms 36, to swing arms 36 and 29 about shafts 30 and 37 with a longitudinal movement of the platen from position below line *a—a* and an accompanying longitudinal movement of inking pad 25 and the perforating mechanism into position substantially in said line whereupon rollers 45 of the crank arm assembly are forced up, by opening of the toggle connection between shafts 40—46 and pin 47 engaging in slot 48 and force the perforator into perforating cooperation with the check and the pad 25, which is above the check, into inking cooperation with the printing characters positioned in line *a—a*. This is accomplished by rotation of shaft 40 through 180 degrees or less in a counter-clockwise direction, Fig. 1, whereupon said shaft is rotated in the opposite direction, swinging the cradle and thereby the inking pad, perforator and platen into the positions shown, whereupon the platen 33 is forced up into cooperation with the printing characters and produces the impression in one of the perforated areas of the check.

The under surfaces of the type bars 7 and 7' are flat as shown at 50 and projecting from said flat surfaces are the numerals, symbols or other printing characters 52. The characters 52 are formed by alternate projecting preferably sharp edged parallel ridges and grooves 53 and 54. The platen 33 extends transversely across the machine substantially normal to the direction of movement of bars 7 and 7' and that portion of its upper surface which cooperates with the printing characters on shiftable bars 7 and 7' and relatively stationary bars 12 and 13 has

transversely thereacross a plurality of alternate preferably sharp edged parallel ridges and grooves 55 and 56.

The grooves and ridges in the printing characters and platen are preferably of sharp substantially V formation although this may be varied, and the grooves of the platen register with the ridges or projections of the printing characters.

When the inking pad is pressed up against the printing characters ink is applied to the edges of the ridges or projections 53 thereof and when the platen is forced up into cooperation with the printing characters with the check or other instrument between them, each character produced upon the check is formed by a plurality of relatively closely spaced parallel and relatively fine lines, as shown in Fig. 9. The character forming lines produced are at the bottom of the parallel lineal depressions formed in the check and parallel lineal protuberances are raised up between said lines. The space in which the impression is made having been preferably already perforated the relatively sharp ridges carry the ink effectively into the raised edges of the perforation and the lineally raised portion of the check produced makes removal or alteration of the impression practically impossible. The check is perforated and the fibers forced out around the perforations and instead of forcing the edges and fibers back into the plane of the check in making the impression, said edges are forced alternately into different planes. The mutilated projecting ridges formed in the check increase the difficulty of reaching the inked lines forming the characters to remove or alter same, and the lineal depressing of said lines increases the difficulty of removing or altering them. The sloping surfaces adjacent the projecting ridges of the type carry the ink into the disrupted edges of the paper.

It should be noted that the grooves and ridges in the printing characters are parallel with each other and with the direction of shifting movement of the type bars. Difficulty in properly registering the ridges and grooves of the platen with the cooperating grooves and ridges of the type is thereby minimized, due to the fact that when proper registration with the ridges and groove in one character is produced, the ridges and grooves in all the other characters are continuations of the same grooves and ridges and equally proper registration will be had with all, as distinguished from movement of one set of ridges and grooves into cooperation with an entirely independently formed set every time the characters are changed to impress a different amount or symbol. To minimize wear along the cooperating ridges and grooves of the platen and type, the sides of frame 5 are struck in

at 60 for cooperation with the opposite ends of the platen and the struck in portions 60 form guides for guiding the grooves and ridges of the platen into proper cooperation 5 with those of the type. Relying upon the cooperating grooves and ridges for registering the platen and type is thereby avoided.

The platen may be guided by pins thereon for cooperation through the check with the 10 type bars or the cooperating grooves and ridges may be otherwise properly registered. It is also within the contemplation of my invention to arrange the lineal ridges and grooves on the type bars 15 about the characters with the character itself recessed or depressed instead of on the printing faces of the characters with the surrounding surface recessed or depressed as shown. The projection of the ridges on the 20 type may be slightly greater than the projection of the ridges on the platen to secure greater force of cooperation along the inked lines produced than along the raised unlinked edges, and the cooperating ridges may be 25 sharp enough to mutilate the paper along the ridges produced therein.

The platen 70 shown in Fig. 4 has a groove 72 extending along its ridged and grooved 30 impressing surface parallel and centrally between the opposite sides thereof so that the impression produced upon the check will be substantially as shown in Fig. 10, the alternate ridges and grooves and inked lines being interrupted centrally. This is especially 35 advantageous in securing an impression of sufficient strength where the paper is mutilated by the alternate grooves and ridges. The characters on bars 12 and 13 are 40 preferably formed substantially like those on bars 7 and 7' and the surface of the platen which cooperates with said characters is grooved and ridged. The characters on bar 45 75 are, however, preferably of the flat faced type and the platen has a flat faced portion cooperable therewith.

I claim:

1. In a check writer, the combination of a platen having a plurality of parallel grooves across its impression face in the direction of its least dimension, a plurality of type bearing bars mounted for longitudinal shifting movement parallel with the grooves in the impression face of the platen and normal to the length of said platen, said 50 type bearing bars each having a plurality of printing character for selective registration with the platen to impress different amounts, said printing characters being defined by grooves in the impression faces of each type bar parallel with each other and parallel with the shifting movement of the type bars, said 55 grooves being parallel with the grooves in the impression face of the platen and the grooves in each type bar being common to all of the printing characters thereon so

that the same grooves cooperate with the grooves in the platen in all of the selective printing positions of each bar.

2. In a device of the class described, a platen having alternate parallel grooves and ridges across one face in the direction of its least dimension, a plurality of parallel type bearing members extending across said platen in the direction of said grooves and ridges and adapted for longitudinal shifting movement parallel the grooves in the platen, said type bearing members each having a plurality of printing characters adapted to be brought selectively into position for cooperation with the platen, said printing characters being defined by alternate parallel grooves and ridges extending longitudinally of the type bearing members and parallel the grooves and ridges in the platen and parallel the shifting movement of the type bars so that the same grooves in the type bars cooperate with the grooves in the platen in all of the selective printing positions of each bar.

3. In a device of the class described, a plurality of type bearing members, a platen, said type bearing members having printing characters adapted to be brought selectively into position for cooperation with the platen, means for effecting relative movement to cause cooperation of the type and platen, a plurality of parallel grooves in the platen and a plurality of ridges defining the printing characters of the type bearing members, said ridges being parallel with said grooves and with each other, also parallel with the movement of the type bars and the ridges at the respective printing characters being continuations of each other, said ridges meshing with the grooves of the platen upon cooperation of the type and platen.

4. In a device of the class described, a transversely disposed platen, a plurality of type bearing members disposed parallel with each other and substantially normal to the platen, said type bearing members having printing characters adapted to be brought selectively into position for cooperation with the platen, and adapted for lineal shifting movement in the direction of their length, means for effecting cooperation of the type and platen, a plurality of parallel grooves in the platen, and a plurality of ridges defining the printing characters of the type bearing members, said ridges being parallel with each other and with the grooves of the platen, also parallel with the lineal shifting movement of the type bars, and adapted for meshing with said grooves when the type and platen cooperate.

5. In a device of the class described, a casing having a check receiving opening, a platen extending transversely through the casing below said opening, a plurality of parallel type bars extending longitudinally

through the casing above said opening, said bars being mounted for longitudinal shifting movement and having printing characters adapted to be brought selectively into position for cooperation with the platen, said characters being defined by parallel ridges extending longitudinally along the type bars parallel with their longitudinal shifting movement, and a plurality of parallel 10 grooves extending across the upper face of the platen in the direction of its least dimension, said grooves being parallel with the direction of shifting movement of the type bars and adapted for meshing with the character defining ridges thereof when platen and type cooperate.

6. In a device of the class described, a platen, a plurality of type bars adapted for longitudinal shifting movement across the platen, said bars having printing characters adapted to be selectively positioned for cooperation with the platen by said longitudinal shifting movement, means for effecting cooperation of type and platen, a plurality 20 of parallel character defining ridges on the impression face of the type bars and a plurality of grooves on the impression face of the platen, said grooves being parallel with each other and with said ridges and adapted 30 for meshing with said ridges upon cooperation of type and platen and both said grooves and ridges being parallel with the shifting movement of the type bars.

7. In a device of the class described, the combination of means for first perforating a thin sheet, and means for thereafter impressing printing characters in the perfor-

rated area, said last means including a platen, and a type bearing bar adapted for longitudinal shifting movement in a direction normal to the length of the platen, said type bearing bar having printing characters defined by a plurality of parallel ridges extending along the impression face of the bar parallel with its longitudinal shifting movement and a plurality of parallel cooperating grooves in the impression face of the platen, said grooves extending in the direction of the least dimension of said face and parallel with the direction of longitudinal shifting movement of the type bar.

8. In a device of the class described, a type bearing member adapted for longitudinal shifting movement, said member having an impression face, printing characters on said face, and alternate grooves and ridges defining said characters, said grooves and ridges extending parallel with each other and parallel with the longitudinal shifting movement of said member.

9. In a device of the class described, a type bearing member adapted for longitudinal shifting movement, said member having an impression face, a plurality of printing characters projecting therefrom, said characters having alternate grooves and ridges on its impression face, said grooves and ridges extending parallel with the other and parallel with longitudinal shifting movement of said member and being common to all of the printing characters on the bar.

In witness whereof, I hereunto subscribe my name this 19 day of February, 1924.

GEORGE M. WILLIS.
